UNITED STATES PATENT OFFICE.

JONATHAN HOWELL AND JOHN WALTER ANDERSON, OF LONDON, COUNTY OF MIDDLESEX, ENGLAND, ASSIGNEES TO EDMUND WRIGHT, JOSEPH WRIGHT, CHARLES S. HOWE, AND GEORGE T. MOXEY, OF PHILADELPHIA, PENNSYLVANIA, AND HARRIS FILSON, OF NEW YORK, N. Y.

DESIGN FOR A HAT-RACK.

SPECIFICATION forming part of Design No. 17,911, dated November 29, 1887.

Application filed October 24, 1887. Serial No. 253,271. Term of patent 7 years.

To all whom it may concern:

Be it known that we, JONATHAN HOWELL and JOHN WALTER ANDERSON, subjects of the Queen of Great Britain and Ireland, and residents of 180 Old Street, in the parish of St. Luke, London, Middlesex, England, have invented a new and original Design for a Rack for Hats, Canes, Umbrellas, &c., of which the following is a specification.

Our design is fully shown in the accompanying drawing, which represents in perspective a rack embodying the design.

The essential features of the design are a bar constituting a representation of a walking-stick or cane and hooks projecting from the face of said bar.

In the rack shown in the drawing three of these bars A are shown, one placed transversely at the top of the rack and the other two depending therefrom adjacent to the ends, each bar representing the natural stick with bark, and having at one end a bent head, a, and at the oppo-

site end a ferrule, b, the hooks B projecting from the face of the stick at intervals between the head and ferrule. 25

We claim—

1. In a design for a hat-rack, the bar A, consisting of the representation of a walking-stick or cane with hooks projecting from the face of the same at intervals from end to end of the bar, 30 all substantially as described and shown.

2. The design for a rack for hats, canes, &c., said design consisting of the transverse bar and pendent bars, each representing a walking-stick or cane with projecting hooks, all substantially as described and shown. 35

In testimony whereof we have signed our names to this specification in the presence of two subscribing witnesses.
